GRINDING MILL

John M. Byers and Daniel T. Swavely,
Flint, Mich.

Application July 22, 1932, Serial No. 624,094

4 Claims. (Cl. 83—22)

This invention relates to a grinding mill designed primarily for the grinding of paint, but it is to be understood that a grinding mill, in accordance with this invention may be employed 5 for any purpose or in any connection for which it is found applicable, and the invention has for its object to provide, in a manner as hereinafter set forth, a mill of the class referred to, so constructed and arranged as to provide for expeditiously and economically grinding paint in a thoroughly satisfactory manner.

Further objects of the invention are to provide, in a manner as hereinafter set forth, a grinding mill which is simple in its construction 15 and arrangement, strong, durable, compact, thoroughly efficient in its use, conveniently operated, readily assembled and comparatively inexpensive to manufacture.

To the above ends essentially, and to others 20 which may hereinafter appear, the invention consists of such parts, and such combination of parts which fall within the scope of the invention as claimed.

In the drawings:

25 Figure 1 is a front elevation, partly in longitudinal section, of the grinding mill.

Figure 2 is a cross sectional view of the grinding mill.

30 Figure 3 is an end view thereof.

Figure 4 is a fragmentary view in side elevation of a modification of the carrier.

Figure 5 is a cross section of the modified form shown in Figure 4.

35 Figure 6 is a fragmentary view in cross section of still another modification of the carrier.

Figure 7 is a fragmentary view in horizontal section showing still another modification of the carrier.

40 Figure 8 is a fragmentary view in section of the modified form shown in Figure 7.

Referring to Figures 1, 2 and 3, the mill includes a pair of spaced parallel frames 1, 2 of inverted V-shape coupled together as at 3. The frames support at their upper ends an operating 45 shaft 4.

The shaft 4 extends outwardly from the frames, and one of the projecting end portions thereof is provided with a fast and a loose pulley 5, 6 respectively adapted to be operated from a prime mover, not shown. The shaft 4 extends through a pair of sleeves 7, 8 and is journaled in the top of frame 2. The sleeve 7 is mounted in the upper end of frame 1. A bearing cap 9 for sleeve 7 is secured upon the top of frame 1. A bearing cap 10 for shaft 4 is secured upon the upper end of frame 2. The sleeve 7 extends outwardly and inwardly with respect to the upper end of frame 1. The sleeve 8 is arranged inwardly of the upper 60 end of frame 2. The sleeves 7, 8 are flanged at

their inner ends, as at 11. The sleeve 7 exteriorly of frame 1 carries a gear wheel 12.

Mounted upon shaft 4 between sleeves 7 and 8 and secured to flanges 11, by holdfast means 13 is an open top, tilttable housing 14 of U-shape cross section having its lower portion 17 of substantially semi-circular contour and its upper portion 17' rectangular. The housing 14 is provided with oppositely disposed, spaced sets 15, 16 of spaced arcuate partitions or arms forming 10 in connection with the lower portion 17 of housing 14, a compartment 18 of cylindrical contour. The partitions are connected to braces 19 and not only form an apertured top for compartment 18, but also retainers for grinding reels to 15 be presently referred to. A removable flanged cover 20 is provided for the open top of housing 14. A handle 21 is secured to cover 20. The end of housing 14 has openings 22 for the passage of shaft 4. Secured to frame 1 is an upstanding 20 angle-shaped supporting arm 23 in which is journaled a shaft 24, the latter having its inner end supported in a bearing 25 anchored to frame 1. Shaft 24 extends outwardly from arm 23 and has its outer end formed with a crank 26 and a 25 handle 27. Shaft 24 is provided with a pinion 28 which meshes with gear 12. The sleeve 7, gear 12, shaft 24, pinion 28, crank 26 and handle 27 provide for tilting housing 14 selectively in opposite directions upon shaft 4 for the purpose 30 of emptying the housing when desired. The spaced partitions or arms provide combined intakes and outlets for said compartment.

Fixed to shaft 4 and bodily rotating therewith is a carrier 29 including a circular row of horizontally disposed channel shaped spaced holders 30 of semi-oval contour and of a length to extend from a point in close proximity from the end 31 to a point in close proximity to the end 32 of housing 14. The carrier includes a pair of 35 spaced hubs 33, 34 which are fixed to shaft 4 and a set of radially disposed arms 35 integral at their inner ends with a hub and at their outer ends with a holder, the latter being arranged in close proximity to the grinding surface 36 provided by the wall of compartment 18. Loosely and revolvably mounted in each holder 30, as well as extending therefrom is a cylinder grinding roll 37 coacting with the surface 36 for grinding the material. The length of each roll corresponds 40 to that of each holder. During the grinding action the rolls 37 revolve. The arms 35 are integral with the holders adjacent the ends of the latter. The partitions act to prevent the rolls 37 from entirely leaving the holders during the rotation of the carrier. The inner faces of the partitions form flush continuations of the grinding surface 36. The upper ends of the partitions of one set oppose in spaced relation the upper 45 ends of the partitions of the other set.

With respect to Figures 4 and 5, the construction of the mill will be the same as that shown in Figures 1, 2 and 3, with this exception that the holders indicated at 38 will be of the same contour as that of the holders 30, but the body of holders 38 will be provided throughout with closely arranged perforations 39 for the passage of the material being acted upon.

The modification shown in Figure 6 relates 10 solely to the holders for the grinding rolls. The holder shown in Figure 6 indicated at 40 is of semi-oval contour, of greater cross sectional length than that of holder 39 and is provided with a pair of superimposed grinding rolls 41, 42, the latter extending from the holder.

The modification illustrated in Figure 7 consists of providing a tubular operating shaft 43 which is adapted to communicate with a fluid supply. The carrier indicated generally at 44 20 will have each of the arms of each set of arms formed of an outer section and an inner section 45, 46 respectively. The section 45 is formed integral at its outer end with a holder 47 of the same form as holder 30. The inner end of section 45 is provided with a piston head 48. The section 46 is tubular and opens at its inner end, as at 49 into the shaft 43. The outer end of section 47 is enlarged as at 50, to provide a piston chamber 51 for the piston head 48. The section 30 45 extends into chamber 51. The arrangement as referred to provides whereby hydraulic pressure can be utilized to keep the grinding rolls in constant pressure against the grinding surface 36. When the form of device shown in Figure 7 35 is employed, a cover 52 is mounted on partitions 15, 16 to arrest the outward movement of the grinding rolls through the openings between the opposed upper ends of the sets of partitions.

On the operation of shaft 4 of 43, the carrier 40 will be bodily moved therewith and carry the grinding rolls for coaction with the grinding surface, whereby the said rolls and surface will act in a manner upon the paint to grind it in a thoroughly efficient manner.

45 What we claim is:—

1. A grinding machine comprising a housing 50 provided with partitions therein to provide in connection with the body of the housing a cylindrical compartment having its wall forming a grinding surface, a carrier rotating in said compartment and provided with a plurality of spaced channel shaped outwardly opening holders, a grinding means loosely and revolvably mounted in each holder and coacting with said grinding surface, said partitions forming a combined intake and outlet for said compartment, a rotatable operating shaft extending through the housing and having said carrier fixedly secured thereto for bodily moving therewith, means mounted on said shaft and connected to said housing for tilting the latter, said shaft being tubular for the reception of a fluid, said carrier formed of extendible parts and non-expendable parts, said shiftable parts being slidably connected in the non-expendable parts, the latter communicating with said shaft to provide for the application of hydraulic pressure to the extendible parts, and said extendible parts including the holders.

2. A grinding machine comprising a housing 70 provided with partitions therein to provide in connection with the body of the housing a cylind-

rical compartment having its wall forming a grinding surface, a carrier rotating in said compartment and provided with a plurality of spaced channel shaped outwardly opening holders, a grinding means loosely and revolvably mounted in each holder and coacting with said grinding surface, said partitions forming a combined intake and outlet for said compartment, each of said holders being perforated throughout, said shaft being tubular for the reception of a fluid, said carrier formed of extendible parts and non-expendable parts, said shiftable parts being slidably connected in the non-expendable parts, the latter communicating with said shaft to provide for the application of hydraulic pressure to the extendible parts, and said extendible parts including the holders.

3. A grinding machine comprising a housing having its lower portion of substantially semi-circular contour, said portion having its inner face providing a grinding surface, oppositely disposed spaced sets of sidewise spaced upstanding arcuate partitions fixedly secured within and spaced throughout from the upper end of the housing, said partitions at their lower ends merging into and extending upwardly from the upper end of said lower portion, the inner faces of said partitions forming flush continuations of the upper ends of said grinding surface, said partitions in connection with said lower portion providing said housing with a cylindrical compartment having a slotted top, said partitions forming combined intakes and outlets for said compartment throughout the top thereof, bracing means within the housing above said partitions and secured to the latter and the ends of the housing, a carrier rotating in said compartment and provided with a plurality of spaced channel-shaped outwardly opening holders, a grinding means loosely and revolvably mounted in each holder and coacting with said surface and inner faces of the partitions for grinding the material, said housing having an open top, a removable closure for said open top, and the upper ends of said partitions and the said bracing means being spaced from 45 said closure.

4. A grinding machine comprising a housing having its lower portion of substantially semi-circular contour, said portion having its inner face providing a grinding surface, oppositely disposed spaced sets of sidewise spaced upstanding arcuate partitions fixedly secured within the housing and extending upwardly from the upper end of said lower portion, the inner faces of said partitions forming flush continuations of the upper ends of said grinding surface, said partitions in connection with the said lower portion providing said housing with a cylindrical compartment having a slotted top, said partitions forming combined intakes and outlets for said compartment throughout the top thereof, a carrier rotating in said compartment and provided with a plurality of spaced channel-shaped outwardly opening holders, a grinding means loosely and revolvably mounted in each holder and coacting with said surface and inner faces of the partitions for grinding the material, and each of said holders having each side thereof provided with spaced perforations throughout.

DANIEL T. SWAVELY. 70
JOHN M. BYERS.
